LOAD TRANSFER DEVICE

Ray Cyrus Yeoman, Lufkin, Tex., assignor to
Texas Foundries, Inc., Lufkin, Tex., a corpora-
tion of Texas

Application February 23, 1945, Serial No. 579,334

6 Claims (Cl. 94-8)

1

This invention relates to load transfer devices and more particularly to devices for transferring loads between adjacent concrete slabs.

Concrete structures such as highways, aircraft runways, building floors and the like have usually been made up of separate slabs which can move relative to each other under expansion and contraction due to temperature changes. Load transfer devices or dowels have been provided at the joints between adjacent slabs to transfer loads from one slab to the other to maintain a smooth, even surface and to prevent breaking of the slabs adjacent the joints. The present invention has for one of its objects the provision of load transfer devices of this type which effectively transmit vertical loads between the slabs and which provide for limited horizontal movement of the slabs relative to each other.

Another object is to provide a load transfer device which is made up of identical units installed in the slabs in reverse relation and which interengage to transfer vertical loads and to limit the horizontal movement between the slabs.

Another object is to provide a load transfer device in which a lateral projecting part on one member is received loosely in an opening in the other member to provide for limited horizontal movement between the slabs.

The above and other objects and advantages of the invention will be more readily apparent from the following description when read in connection with the accompanying drawing, in which—

Figure 1 is a vertical section through a joint between adjacent slabs illustrating a load transfer device embodying the invention with parts omitted;

Figure 2 is a horizontal section through Figure 1 looking from the bottom;

Figure 3 is a perspective view illustrating the load transfer device of Figures 1 and 2; and

Figures 4 and 5 are views similar to Figure 3 showing alternative constructions.

As illustrated in Figures 1 and 2, a pair of concrete slabs 10 and 11 meet at a joint filled with a yielding filler material 12 such as impregnated paper, compressed wood or the like. The material 12 fits closely against the adjacent faces of the slabs to seal the joint against water or the like and is adapted to be compressed and to expand as the slabs move to maintain the joint tight.

The slabs are connected by load transfer devices made up of identical members installed in the slabs in reverse relation to each other and

2

extending through openings in the filler strip 12 to transfer loads between the slabs. In the form shown in Figures 1 to 3, the members comprise main body or anchor portions 13 adapted to be imbedded in the slabs and terminating in flat front faces to abut against the filler strip 12. The main body or anchor portions may be held in the slabs by angularly extending arms 14 which project therefrom and which may be imbedded in the slabs to hold the body portions securely therein. The arms may be roughened or formed with projections or the like as desired to anchor them more firmly in the concrete.

The body portion of each member is formed in one face with a recess extending substantially half way through the thickness of the body to leave horizontal upper or bearing shoulders 15 and lower shoulders 15a. A transverse opening 16 connects with the recess and is of greater width than the recess to form vertical shoulder portions 17.

Each of the members is formed with an integral projecting portion or cantilever bridging member 18 of substantially half the thickness of the body portion 13 to extend outwardly from the body portion through the opening in the sealing strip 12 and into the anchor or body portion of the opposite member. The projecting portions 18 are of such a size and shape as to slidably engage the bearing shoulder 15 and to have a slight clearance from the shoulders 15a. Each projecting portion is formed at its outer end with a crossbar part 19 extending laterally from the projecting portion.

In assembling the members, the projecting portion 18 of each member is assembled in the recess in the face of the other member with the crossbar part 19 fitting in the opening 16 of the other member. As clearly shown in Figure 1, the crossbar part 19 is smaller than the opening so that it may have limited movement therein before it strikes either the shoulders 17 or the rear wall of the opening 16. The parts are initially assembled in substantially the relationship shown in Figure 1 in which the crossbar parts 19 lie centrally in the openings 16 and the upper or bearing shoulders 15 engage the upper or bearing surfaces of the projecting portions 18. The members of the load transfer devices may be assembled prior to pouring of the concrete in the position shown and may be held in place by suitable stakes or spools while the concrete is poured around them. Preferably during pouring of the concrete, plates or sheets 21 of metal, paper or the like are laid over the recesses and

openings 16 to prevent filling of the same with concrete. Alternatively the recesses and openings 16 may be filled with elastic or plastic material around the portions 18 and 19 to prevent filling with concrete.

In operation any vertical load on one of the slabs adjacent the joint will be transmitted to the other slab through the bearing shoulder 15 and projecting part 18 so that the slabs are held in proper vertical alignment and so that the edge portions of the slabs adjacent the joints will not readily break under load. Upon changes in temperature causing expansion or contraction of the slabs, the joints will tend to move together or to separate. This will cause the projecting portions 18 to slide over the bearing shoulders 15 without interrupting the transmission of load between the slabs. In the event the slabs should tend to separate to an undesired extent, the crossbar portions 19 engage the shoulders 17 formed by the openings 16 to restrict relative movement of the slabs to such an extent that the sealing material 12 would lose contact with the slab faces. This construction prevents excessive movement of the slabs which might cause the joints to open up excessively and serves to minimize dragging of any one slab an excessive amount on the sub-grade in the event all of the joints should not function properly. The expansion and contraction is, therefore, distributed more or less uniformly throughout the entire structure and the expansion filler between all of the joints is maintained under corking pressure.

In the construction illustrated in Figure 4 the load transfer members include body portions 22 adapted to be anchored in the slabs in the same manner as the body portions 13 of Figures 1 to 3. Angularly projecting roughened arms 23 project from the body portions 22 to assist in anchoring them in the slabs. Each member has one face of its body portion cut away as indicated at 24 to form a recess bounded on one side by a horizontal shoulder 25 and is formed adjacent the end of the recess with a transverse opening 26 extending horizontally through the body portion.

Each member is formed with a bridging portion 27 substantially half the thickness of its body portion adapted to fit into the recess 24 on the opposite member with its upper edge resting against the shoulder 25 to transmit vertical loads between the slabs. At its outer end, each of the bridging portions is formed with a laterally extending head 28 adapted to enter the opening 26 of the opposite member and to fit loosely therein.

The load transfer members of Figure 4 are adapted to be assembled in the slabs in substantially the same manner as illustrated in Figures 1 and 2 with the bridging portion 27 of each member resting against the shoulder 25 of the other member and with the head part 28 of each member fitting loosely into the opening 26 in the other member. As shown, the openings 26 are vertically elongated so that the head parts 28 can move vertically therein. This construction operates substantially like that of Figures 1 to 3, the head parts 28 moving in the openings to provide for limited horizontal movement between the slabs.

The construction of Figure 5 is similar to that of Figure 4 and includes a pair of members each having a body or anchor portion 31 adapted to be anchored in the slabs by angularly projecting arms 32. Each body is formed with relatively deep recess bounded by horizontal shoulders 33 and has a horizontal opening 34 extending partially

through the body portion at the inner end of the recess

Bridging portions 35 substantially half the width of the body portions project therefrom to enter the recesses in the opposite members with the upper and lower surfaces thereof slidably engaging the bearing shoulder 33 and clearing companion shoulder 33a. The outer end of each bridging portion is turned over as indicated at 36 to enter the opening 34 of the opposite member. The turned parts 36 are preferably smaller than the openings 34 to provide for limited horizontal movement. In operation, the device shown in Figure 5 functions in substantially the same manner as the device of Figures 1 to 4 to transmit vertical loads between the slabs and to limit relative horizontal movement of the slabs.

While several embodiments of the invention have been shown and described in detail, it will be understood that these are illustrative only and are not intended as a definition of the scope of the invention, reference being had for this purpose to the appended claims.

What is claimed is:

1. A load transfer device adapted to be imbedded in adjoining concrete slabs for transferring loads therebetween and for limiting separation thereof comprising a pair of identical integral members, each member including an anchor portion adapted to be imbedded in one of the slabs and a longitudinal bridging portion extending into the anchor portion of the other member and adapted to span the joint between the slabs, the anchor portion of each member being formed with a longitudinal recess longitudinally slidably to receive the longitudinal bridging portion of the other member and adapted to transfer vertical loads between the adjacent slabs and having an opening extending transversely from the recess, and a transversely projecting part on each of the bridging portions entering the opening in the other member, the longitudinal dimension of the transversely projecting parts being substantially less than the longitudinal dimension of the transversely extending openings for providing limited longitudinal relative movement of the pair of members and adapted to provide limited separation of the adjacent slabs.

2. A load transfer device adapted to be imbedded in adjoining concrete slabs for transferring loads therebetween and for limiting separation thereof comprising a pair of identical integral members, each member including an anchor portion adapted to be imbedded in one of the slabs and a longitudinal bridging portion extending into the anchor portion of the other member and adapted to span the joint between the slabs, the anchor portion of each member being formed with a longitudinal recess longitudinally slidably to receive the longitudinal bridging portion of the other member and adapted to transfer vertical loads between the adjacent slabs and having an opening extending transversely from the recess, and a transversely projecting part on each of the bridging portions entering the opening in the other member, the longitudinal dimension of the transversely projecting parts being substantially less than the longitudinal dimension of the transversely extending openings for providing limited longitudinal relative movement of the pair of members and adapted to provide limited separation of the adjacent slabs and a seal for the transversely extending openings adapted to prevent concrete from entering the same.

3. A load transfer device adapted to be imbedded in adjoining concrete slabs for transferring loads therebetween and for limiting separation thereof comprising a pair of identical integral members, each member including an anchor portion adapted to be imbedded in one of the slabs and a longitudinal bridging portion extending into the anchor portion of the other member and adapted to span the joint between the slabs, the anchor portion of each member being formed with a longitudinally arranged T-shaped recess, and a cross part at the end of each of the bridging portions, the bridging portion of each member longitudinally slibably fitting into the recess of the other member and adapted to transfer vertical loads between the adjacent slabs, and the longitudinal dimensions of the cross parts being substantially less than the longitudinal dimension of the T-shaped recesses for providing limited longitudinal relative movement of the pair of members and adapted to provide for limited separation of the adjacent slabs.

4. A load transfer device adapted to be imbedded in adjoining concrete slabs for transferring loads therebetween and for limiting separation thereof comprising a pair of identical integral members, each member including an anchor portion adapted to be imbedded in one of the slabs and a longitudinal bridging portion extending into the anchor portion of the other member and adapted to span the joint between the slabs, the anchor portion of each member being formed with a longitudinal recess longitudinally slidably to receive the longitudinal bridging portion of the other member and adapted to transfer vertical loads between the adjacent slabs and having a single opening extending transversely from the recess, and a single transversely projecting part on the end of each of the bridging portions entering the opening in the other member, the longitudinal dimension of the transversely projecting parts being substantially less than the longitudinal dimension of the transversely extending openings for providing limited longitudinal relative movement of the pair of members and adapted to provide limited separation of the adjacent slabs.

5. In combination with a pair of adjoining concrete slabs, a load transfer device imbedded in the adjoining slabs and comprising a pair of identical integral members, each including an anchor portion imbedded in one of the slabs and a longitudinal bridging portion spanning the joint between the adjacent slabs and extending into the

55

anchor portion of the other member, the anchor portion of each member being provided with a longitudinal recess longitudinally slidably to receive the longitudinally bridging portion of the other member for transferring vertical loads between the adjacent slabs and having an opening extending transversely from the recess, and a transversely extending part on each of the bridging portions entering the opening in the other member, the longitudinal dimension of the transversely projecting parts being substantially less than the longitudinal dimension of the transversely extending openings for providing limited longitudinal relative movement of the pair of members and limited longitudinal separation of the adjacent slabs.

10 6. In combination with a pair of adjoining concrete slabs, a load transfer device imbedded in the adjoining slabs and comprising a pair of identical integral members, each including an anchor portion imbedded in one of the slabs and a longitudinal bridging portion spanning the joint between the adjacent slabs and extending into the anchor portion of the other member, the anchor portion of each member being provided with a longitudinal recess longitudinally slidably to receive the longitudinal bridging portion of the other member for transferring vertical loads between the adjacent slabs and having an opening extending transversely from the recess, and a transversely extending part on each of the bridging portions entering the opening in the other member, the longitudinal dimension of the transversely projecting parts being substantially less than the longitudinal dimension of the transversely extending openings for providing limited longitudinal relative movement of the pair of members and limited longitudinal separation of the adjacent slabs, and a seal for the transversely extending openings for preventing concrete from entering the same.
